UNITED STATES PATENT OFFICE.

LOUIS H. FLANDERS, OF JENKINTOWN, PENNSYLVANIA.

PORTABLE BATTERY.

1,230,390.

Specification of Letters Patent. Patented June 19, 1917.

Application filed March 22, 1917. Serial No. 156,580.

To all whom it may concern:

Be it known that I, LOUIS H. FLANDERS, a citizen of the United States, residing at Jenkintown, in the county of Montgomery and State of Pennsylvania, have invented certain new and useful Improvements in Portable Batteries, of which the following is a specification.

The principal object of the present invention is to provide a portable battery which can be placed in any position, even up-side-down, without danger of leakage and with proper ventilation while at the same time the plate space may be filled so as to increase the capacity without substantial increase in height or outside dimensions.

The invention will be claimed at the end hereof but will be first described in connection with the embodiment of it chosen from among other embodiments for the sake of illustration in the accompanying drawings in which—

Figure 1, is an elevational view, partly in section and taken on the line 1—1, of Fig. 3. Fig. 2, is a transverse sectional view of Fig. 1.

Fig. 3, is a top or plan view partly in section.

Fig. 4, is a section on the line 4—4, of Fig. 3, showing a part of the battery, and Fig. 5, is a similar view taken on the line 5—5, of Fig. 3.

The cell is sub-divided by partitions 1, extending from the top to the bottom thereof into a plate space 2, and gas space 3, and chambers *a* and *b*. The cell is provided with ventilation tubes or passages 4 and 5, communicating with the air, as through the vent openings 6, of plugs 7, and extending into the middle portions of the chambers *a* and *b*. In the cover 8, are oppositely disposed vent tubes or passages 9 and 10, one of which opens to the gas space 3, adjacent to one corner and extends and opens into the ventilation chamber *b*, near the end thereof and whereof the other opens to the gas space 3, at or adjacent to the diagonally opposite corner and extends and opens into the other ventilation chamber *a*, near the end thereof. The portions of the vent tubes or passages 9 and 10, adjacent the cover 8, are inclined from their communication with

the gas space away from the interior of the cell to provide for drainage. Evidently the plate structure 11, is substantially as high 55 as the cell so that the plate space is large leaving but a small gas space above commensurate in size with the space left in ordinary batteries. In this way the capacity of the battery is relatively large in proportion to its size considered as a portable battery. The ventilation chambers *a* and *b*, do not add to the height of the battery and they add very little to its other dimensions since portable batteries are frequently 60 rounded so as to fit other appliances or for other reasons. To take an extreme case, if the battery is turned up-side-down the level of the electrolyte will be below the upper ends of the tubes or passages 9 and 10, so 65 that no liquid will escape. If the battery be turned on its side the liquid level will fill that portion of one of the tubes 9 and 10, that is adjacent to the cover but will not reach the other tube or passage, so that the 70 latter remains effective for ventilation by way of the ventilation chamber with which it communicates. If in course of time the fluid reaches the ventilation chambers *a* and *b*, it may not readily escape therefrom 75 through the openings 6, because the tubes or passages 4 and 5, project well into those chambers and project above the level of the liquid therein even when the battery is turned up-side-down. If, however, an excess of liquid collects in the chambers *a* or *b*, considerable time would be required and at the end of that time it can be drained off by the removal of the plugs 7. The result 80 of the improvement is that the battery can be violently shaken and turned into any position that it would naturally get into in the course of its use without spilling liquid. For instance, the battery can be used by miners and carried on their backs without 85 spilling liquid. When the battery is in upright position, it is ventilated by way of the passages 9 and 10, the chambers *a* and *b*, and tubes 4 and 5, and as it is inclined from 90 that position either one or the other of the sets of tubes remains operative.

What I claim is:

A storage battery cell sub-divided into plate and gas spaces and chambers provided

with ventilation tubes or passages communicating with the air and opening and extending into the middle portions of the chambers, and having in its cover oppositely disposed vent tubes or passages one of which opens to the gas space of the cell at or adjacent to one corner and extends and opens

into one chamber near the end thereof and whereof the other opens to the gas space of the cell at or adjacent to the diagonally opposite corner and extends and opens into the other chamber near the end thereof, substantially as described. 10

LOUIS H. FLANDERS.
